United States Patent Office

Des. 232,262
Patented July 30, 1974

232,262

SPECTACLE FRONT

Jack Bloch, Leominster, Mass., assignor to Foster Grant Co., Inc., Leominster, Mass.

Filed Sept. 14, 1973, Ser. No. 397,560

Term of patent 14 years

Int. Cl. D16—06

U.S. Cl. D57—1 F

FIG. 1

FIG. 2

FIG. 3

FIG. 1 is a front elevational view of a spectacle front showing my new design.

FIG. 2 is a top plan view thereof.

FIG. 3 is a side elevational view thereof.

The rear of the spectacle front, not shown, conforms in configuration to the front shown.

The side not shown has substantially the same appearance as the side shown.

I claim:

The ornamental design for a spectacle front, substantially as shown and described.
